UNITED STATES PATENT OFFICE.

ANTHONY F. SCHOOL, OF SOUTH KAUKAUNA, WISCONSIN.

PORTABLE SAW.

1,309,781.

Specification of Letters Patent. Patented July 15, 1919.

Application filed May 3, 1918. Serial No. 232,232.

To all whom it may concern:

Be it known that I, ANTHONY F. SCHOOL, a citizen of the United States, and resident of South Kaukauna, in the county of Outagamie and State of Wisconsin, have invented 5 certain new and useful Improvements in Portable Saws; and I do hereby declare that the following is a full, clear, and exact description thereof.

10 My invention relates to new and useful improvements in power driven saws, particularly those of a readily portable nature.

At the present time most saws of this general type are so constructed that they can 15 only operate upon a log of wood or the like when the same is positioned horizontally. It is therefore the principal object of the present invention to provide a saw which will operate either when it is positioned vertically or horizontally.

It is also an object of this invention to provide means for regulating the height of the cutting edge of the saw above the surface of the ground so that logs or the like of different diameters may be cut with equal facility.

A still further object is to provide means for retaining the cutting edge of the saw substantially parallel to the ground irrespec- 30 tive of height of the same thereabove.

With these and other objects in view the invention resides in the novel features of construction, combination and arrangement of parts which will be hereinafter more particularly described and claimed.

In the accompanying drawings Figure 1 represents a front elevational view of a portable power driven saw constructed in accordance with my invention, the parts being positioned to cut a log disposed horizontally.

Fig. 2 is a plan view of the parts illustrated in Fig. 1.

Fig. 3 is a side elevational view of the invention illustrating the two positions in which the saw carriage may be disposed.

Figs. 4 and 5 are detail transverse sectional views taken respectively on the plane of the lines 4-4 and 5-5 of Fig. 2, and

50 Fig. 6 is an enlarged detail sectional view showing particularly the means for slidably connecting the saw carriage adjusting member with the saw carriage frame.

Referring more particularly to the accompanying drawings in which similar reference characters indicate like parts throughout the several views, 1 denotes a supporting frame preferably rectangular in plan view which may be constructed of any desired material, and is supported at one end by a 60 pair of ground engaging wheels 2 and at its other end by a leg 3. At one end of the supporting frame is disposed an internal combustion engine E, the shaft 4 of which is extended and has its free end journaled in a 65 suitable bearing 5.

At the opposite end of the supporting frame and adjacent the side edges thereof is a pair of alined bearings 6 in which a transverse shaft 7 is mounted, said shaft being 70 preferably disposed parallel to the shaft 4. Each of said shafts has a sprocket wheel 8 fixed thereto, which sprocket wheels are connected by a chain or the like 9. The shaft 7 forms a pivot for a saw carriage frame 10, 75 the latter being adapted to be disposed either in a horizontal position as indicated in Fig. 2 and in the full lines in Fig. 3, or vertically as shown by the dotted lines in the last mentioned figure. The carriage 80 frame 10 in turn carries a shaft 11 having at its outer end a crank 12. The inner end of said shaft 11 has a bevel gear 13 fixed thereto, the teeth of which are continuously in mesh with those of a bevel pinion 14 fixed 85 to the shaft 7. Thus it will be seen that upon the operation of the engine E, the shaft 4 will be rotated, the movement of which will be transmitted to the crank 12.

A standard 14^a extends upwardly from 90 the saw carriage frame, when the latter is in a horizontal position, and has one end of an arcuate bracing strip 14 fixed thereto, the other end of said strip being secured to the under side of an arm 15 which projects laterally from one end of a frame 10. The center of the arc on which the brace strip is constructed is the shaft 11 whereby said strip may be used as a guide in a manner to be hereinafter more particularly described. 100

Pivotedly mounted on the end of the shaft 11 adjacent the crank 12 is a channeled bar 16 which forms a saw carriage adjusting member for a saw carriage 17. One end of the channeled bar is preferably secured to 105 a casting 18 which is pivoted on the shaft 11

while the other end has a hub casting 19 secured thereto. The saw carriage 17 is also formed from a channeled bar and from its intermediate portion projects a spindle 20, the same being journally mounted in the hub casting 19.

A suitable saw S is reciprocatorily carried by the saw carriage 17, one end being linked as at 21 to a guide block 22 which 10 slides longitudinally and between the flanges of said carriage, being held in the carriage by clip plates 22^a secured thereto and embracing the carriage. This block and the saw are reciprocated by the rotation of the 15 crank 12 which is connected thereto by a pitman 23 secured on a pivot bolt 23^a passed through the saw, the outer clip plate 22^a and the guide block 22. The saw is further guided during its movement by the sliding 20 engagement of its upper edge with the hooked free end of an arm 24 which is carried by one end of the saw carriage 17. From this it will be seen that the rotative movement of the shaft 4 is readily transmitted to the saw S for operation upon a log or the like L.

As hereinbefore mentioned the saw carriage is adjusted so that the saw may readily operate on logs of different diameters. For 30 this purpose a lever 25 is secured to the casting 18 so that the saw carriage adjusting member may be oscillated about the shaft 11; such movement obviously raises or lowers the free end of the member 16 and consequently the saw carriage 17 and the saw S. The adjusting member 16 is held in any one of its several positions by the engagement of a pawl 26 carried by the lever 25 with the ratchet teeth of a sector 27 secured to the saw carriage frame 10. The pawl 26 is readily released in a conventional manner.

After the member 16 is adjusted the saw carriage 17 is shifted until it is positioned 45 approximately parallel with the ground. The saw is at the same time moved to a similar position and thus there will be no tendency of one end of the latter engaging the ground as is liable to be the case if such 50 adjustment is not provided. The saw carriage is rocked by means of said spindle 20 and hub 19 when the lever 28 is moved. This lever 28 is positioned in sliding engagement with the lever 25 and carries a detent 55 29 for coöperation of any one of a plurality of holes 30 formed therein. In order that this co-action between the detent 29 and the holes 30 may readily be carried out, the lever 25 is arcuate, the center of the arc being the 60 spindle 20.

The saw carriage adjusting member 16 has its free end portion held against lateral movement and is guided when swung about the shaft 11 by the engagement of a channeled guide 31 with the brace strip 14. Fig.

6 clearly illustrates this feature of the invention.

A rod or bar 32 has one end portion slidably and pivotally engaged with the upper end of the standard 13 and its other end 70 carries a spike member 33. Said member 33 is adapted to be driven into the log L or the article which is being sawed as clearly shown in Fig. 1; this prevents rotation of the log and holds it relatively stationary.

When the article to be sawed is disposed upright, as for instance a growing tree, the saw S is moved to position it horizontally. This is carried out by moving the saw carriage frame 10 from its normal horizontal 80 position to a vertical position as indicated by the broken lines in Fig. 3. This movement will dispose the free end of the standard 13 over the engine E and between the wheels 2. The parts are braced in this position by the 85 engagement of said standard 13 with the upper end of a post 34, the lower end of which is preferably pivoted to the supporting frame 1. A detachable link 35 secures the standard and post together to prevent 90 the saw carriage frame from returning to its normal horizontal position.

From the foregoing description taken in connection with the accompanying drawings it will be readily seen that a very simply 95 constructed portable power driven saw has been devised and that the same will be much more efficient than the usual device of this character inasmuch as it may be readily operated to saw logs and other articles both 100 when they are disposed horizontally and when in a vertical position.

I claim:—

1. A sawing machine comprising a main frame, a member pivoted on the main frame 105 for vertical swinging movement, a second member pivoted on the first member for vertical swinging movement, a saw movably carried by said second member, a drive means on the main frame, a drive connection 110 between the drive means and saw operative in various relative positions of said members and main frame, a lever connected with the first named member for swinging the same, said lever being curved substantially on an 115 arc having as its center the pivotal connection of the said two members, a lever carried by the said second named member and transversing the first lever, means for holding the first named lever adjustably against 120 swinging movement, and means carried by the second named lever and engageable with selective portions of the first named lever for holding said levers against relative movement.

2. A sawing machine comprising a main frame, a drive shaft journaled on the main frame, a second frame pivotally mounted on the drive shaft, a second shaft carried by the second frame and extending transversely 130

of the first shaft, a drive connection between said shafts, a saw carrying member pivoted on the second shaft, a saw movably carried by said member, a drive connection 5 between the saw and the second named shaft, means for holding the second named frame against movement relative to the first frame, and means for adjustably holding the saw

carrying member against movement relative to the second named frame. 10

In testimony that I claim the foregoing I have hereunto set my hand at South Kaukauna, in the county of Outagamie and State of Wisconsin.

ANTHONY F. SCHOOL.
